FOREIGN PATENT DOCUMENTS

GB 2529487 A 2/2016

Primary Examiner — Kevin K. Rudzinski*Assistant Examiner* — Amber J Rabie(74) *Attorney, Agent, or Firm* — David A. Jones; Nadesan Beck P.C.(57) **CLAIM**

The ornamental design for a protective garment, as shown and described.

DESCRIPTION

FIG. 1 is a front view of the protective garment showing our new design;

FIG. 2 is a left side view thereof, a right side being identical to the left side;

FIG. 3 is a rear view thereof;

FIG. 4 is a front view thereof, with sleeves of the protective garment outstretched;

FIG. 5 is a rear view thereof, with the sleeves outstretched; and,

FIG. 6 is a front-left perspective view thereof.

The broken lines in the figures are for illustrating environmental structure and form no part of the claimed design.

1 Claim, 6 Drawing Sheets(56)
